(57) **CLAIM**

The ornamental design for a traction mat, as shown and described.

DESCRIPTION

FIG. 1 is a perspective view taken from the top left of the traction mat;

FIG. 2 is a top plan view of the traction mat of FIG. 1;
FIG. 3 is a bottom plan view of the traction mat of FIG. 1;
FIG. 4 is a right elevational view of the traction mat of FIG. 1;

FIG. 5 is a left elevational view of the traction mat of FIG. 1;

FIG. 6 is a front elevational view of the traction mat of FIG. 1;

FIG. 7 is a back elevational view of the traction mat of FIG. 1;

FIG. 8 is a perspective view taken from the top of the traction mat of FIG. 1;

FIG. 9 is an enlarged partial perspective view taken from the top left of the traction mat of FIG. 1;

FIG. 10 is a perspective view taken from the top left of the traction mat of FIG. 1 in a partially folded state;

FIG. 11 is a perspective view taken from the top of the traction mat of FIG. 1 in a partially folded state;

FIG. 12 is a perspective view taken from the top left of the traction mat of FIG. 1 in a folded state; and,

FIG. 13 is a perspective view taken from the top of the traction mat of FIG. 1 in a folded state.

1 Claim, 11 Drawing Sheets
